UNITED STATES PATENT OFFICE.

LAURANCE H. STURTEVANT, OF QUINCY, MASSACHUSETTS, ASSIGNOR TO STURTEVANT MILL COMPANY, A CORPORATION OF MAINE.

MIXING APPARATUS.

1,159,607.

Specification of Letters Patent.

Patented Nov. 9, 1915.

Application filed October 7, 1914. Serial No. 865,482.

To all whom it may concern:

Be it known that I, LAURANCE H. STURTEVANT, a citizen of the United States, residing at Quincy, in the county of Norfolk and 5 State of Massachusetts, have invented or discovered certain new and useful Improvements in Mixing Apparatus, of which the following is a specification, reference being had therein to the accompanying drawings. 10 This invention relates to an improved mixing apparatus more especially intended for mixing fertilizers, but which may be used for other purposes, if desired and by means of which the various ingredients may 15 be prepared, mixed and discharged. These results are effected in a most perfect manner by a combination of coöperating machines, as will hereinafter appear, and the plant is made flexible so that by a few adjustments 20 it may be made to serve several purposes. To these ends the improved apparatus, in its preferred form, comprises a breaking feeder located in a hopper into which the ingredients to be mixed are placed, and 25 which breaking feeder will deliver the crushed material to a well or elevator boot from which it is taken by an elevator which delivers the material to a screen or separator, from which the fine material is delivered to 30 a hopper communicating with a rotating mixer, the clods or tailings from the screen or separator being delivered to a crusher from whence they pass to the said elevator, and thence back to the separator. After the 35 fertilizer ingredients have been properly mixed they may be discharged from the mixer directly to any desired point, as to a bin or hopper over weighing and bagging scales, or to a conveyer which will carry the 40 same to a storage bin, or the mixed material may be delivered from the mixer to a second elevator which will discharge the same to any desired point.

In the accompanying drawings Figure 1 is 45 an elevation of an apparatus embodying one form of the present invention, and Fig. 2 is a side view of the same looking from the left of Fig. 1. Fig. 3 is an elevation of an apparatus embodying another and somewhat 50 simpler form of the invention, and Fig. 4 is a side view of the same looking from the left of Fig. 3.

Referring to the drawings, 12 denotes a 55 hopper into which the ingredients to be mixed, and which are usually in ground or pulverized form, but more or less caked, or

in clods or lumps, are dumped. At or adjacent to the discharge mouth of the hopper 12 is located a rotating breaking feeder 13 which crushes the lumps or clods more or less, and delivers the material in a regulated flow to a well or elevator boot 14 from whence it is taken by an elevator 15 which delivers the same through a spout 16 to a screen or separator 17. The elevator 15 is 60 of well-known form comprising an endless belt or chains provided with buckets, and the separator 17 will preferably be the well-known Sturtevant or Newaygo separator comprising an inclined sieve or sieves and 65 means for percussively jarring the same.

The "fines" or fine material from the separator 17 are delivered to a mixer hopper 18 where they are held awaiting the return of the tailings or clods which have been separated by the screen 17, and which tailings or clods pass through the spout 21 to a rotating pulverizer or clod breaker 22 which discharges through spout 23 into the shaft of the elevator 15 and to the boot or well 14, 80 whence it is again conveyed to the separator 17, and being now in finely pulverized condition will pass to the mixer hopper 18 where it rejoins the batch from which it was temporarily separated by the screen 17. The 85 batch is now completely assembled in the mixer hopper, and a sliding gate 33, with which the said mixer hopper is provided, is opened, and the entire batch passes into the closed rotating drum mixer 20 through spout 90 19, where it is thoroughly mixed together, so that the desired proportions of the different ingredients will be contained in the mixed material. The rotating mixer 20 will 95 preferably be of the well-known Sturtevant or Hunso type, and the pulverizer or clod breaker 22 will preferably be of the swinging hammer type, such, for example, as that shown by U. S. Patent No. 686,364.

When the materials have been thoroughly 100 mixed the mixer discharge gate is opened and the mixture passes through a spout or chute 24 located below the mixer and communicating with the boot or well of a second elevator 25 which discharges into an 105 adjustable spout or chute 26 the position of which may be changed so as to deliver the material to any practicable point, as to a bin or hopper 27 placed above a weighing and sacking device 28, or to a conveyer 29 which 110 will carry the same to a storage bin.

After mixed fertilizers have been stored

for some time they frequently become more or less caked or hardened, so that it is desirable that they should be broken up or pulverized, but they do not require further mixing. In such case the apparatus above described may be used for this purpose, and to this end the mixer hopper 18 preferably communicates with a discharge spout 30 through an opening closed by a hinged gate 31 operated by a handle 32, said gate being closed during the mixing operation but being opened when it is desired to discharge the material directly from the mixer hopper 18 to the elevator 25 which discharges to the 15 sacking and weighing bin 27 or the conveyer 29. The sliding gate 33 by which the passage from the mixer hopper 18 may be closed, will be open during the mixing operation, but will be closed when it is desired to cut off communication between the 20 said hopper 18 and the mixer 20, so as to hold the material in the mixer hopper until an entire batch of material has been passed through the separator and is in proper condition to be mixed. As a convenient means 25 for opening and closing said gate the latter may be provided with a rack 34 with which meshes a pinion 35 operated by a hand wheel 36.

30 In order that the flexible or adjustable spout 26 may be readily adjusted to different positions, so as to discharge into the hopper or bin 27, or to the conveyer 29, it is preferably provided with a swivel mounting, as shown in Fig. 1, which permits said spout to be turned about horizontally to any desired position.

In the form of the invention shown in Figs. 3 and 4 the second elevator 25 is omitted, 40 and the mixed material may be discharged from the mixer 20 through the mixer discharge spout 24 directly into the bin or hopper 27, or it may be discharged from the mixer hopper 18 through an adjustable spout 45 37 either into the said bin or hopper 27, or to the endless conveyer 29. To this end the said spout 37 will preferably be provided with a swiveled connection with its support, like that of the spout 26, so that it may be 50 turned to different positions.

In the operation of the apparatus the rotating feeding breaker 13 will, to a considerable extent, prevent dust from escaping from the shaft of the elevator 15, in that 55 the discharge mouth of the hopper 12 will usually be closed by the entering material and by the said breaker, the latter tending to cause an inward draft, so as to diminish the discharge of dust from the shaft of the elevator 15. The shafts of the elevators 15 and 60 25 will preferably be made tight and dust-proof, and of sheet steel, and as the casing of the separator 17 and the other parts or spouts through which the material must pass 65 will also preferably be made dust tight, it

will be seen that the apparatus may be operated so that there will be little or no dust, which, as will readily be understood, is very desirable. This mixing unit insures the delivery of all the ingredients, of which the 70 batch consists, to the mixer at the same time, thus keeping each batch absolutely separate from the others, which is of prime importance, in fact, the only method which can give correct results. This is achieved by 75 the special arrangement of the coöperating machines or parts of the improved mixing apparatus and their rapid and thorough co-operating action of each machine, so that the entire plant operates as a unit. 80

Another feature of great importance of the improved apparatus is its flexibility, for by simply closing and opening one or two gates and the shifting of a flexible or adjustable spout the following results may be 85 accomplished in a fertilizer mixing plant: 1st. To rapidly mix, weigh, bag and make ready to ship complete fertilizers as a continuous process. 2nd. To mix and carry fertilizers to storage until chemical action ceases. 3rd. To remix, remill, weigh, bag and make ready to ship stored fertilizers. 4th. To remill, screen and make ready to ship aged or stored fertilizers without further mixing. 90

95 The invention is not to be understood as being limited to the details of construction herein shown and described, as these may vary widely, within the province of mechanical skill, without departing from the spirit and scope of the invention.

Having thus described my invention I claim and desire to secure by Letters Patent:

1. In a mixing apparatus, the combination 105 with a hopper for the reception of material to be mixed, of a crushing feeder adjacent the discharge mouth of said hopper, an elevator to which the material is delivered by said crushing feeder, a separator 110 to which the said elevator discharges, a mixer communicating with said separator, a clod breaker for crushing the tailings or clods discharged from said separator, and means for delivering the mixed material to 115 a receptacle or conveyer.

2. In a mixing apparatus, the combination 120 with a hopper for receiving the materials to be mixed, means for feeding the said materials from said hopper, an elevator to which said materials are delivered by said feeding means, a separator to which said elevator discharges, a mixer hopper below said separator, a mixer with which said hopper may be placed in communication through a delivery spout or passage to said mixer, a second delivery spout from said hopper, a clod breaker for crushing the tailings or clods discharged from said separator, and a spout 125 for delivering the mixed material when the 130

- same is discharged from said mixer, said mixer hopper being provided with gates which may be opened to enable the material to be delivered to the said mixer, or, when 5 the gate to the mixer is closed, to deliver the material through said second delivery spout.
3. In a mixing apparatus, the combination with a hopper for the reception of material to be mixed, of a crushing feeder adjacent the discharge mouth of said hopper, an elevator to which the material is delivered by said crushing feeder, a separator to which the said elevator discharges, a mixer communicating with said separator, a clod breaker for crushing the tailings or clods discharged from said separator, a second elevator to which the material may be delivered from said mixer, and means for finally delivering the mixed material to a receptacle 10 or conveyer.
4. In a mixing apparatus, the combination with a hopper for receiving the materials to be mixed, means for feeding the said materials from said hopper, an elevator to which said materials are delivered by said feeding means, a separator to which said elevator discharges, a mixer hopper below said separator, a mixer with which said hopper may be placed in communication 15 through a delivery spout or passage to said mixer, a second delivery spout from said hopper, a clod breaker for crushing the tailings or clods discharged from said separator, a spout for delivering the mixed material 20 when the same is discharged from said mixer, a second elevator to which the material may be delivered by said last-named spout, said mixer hopper being provided with gates which may be opened to enable 25 the material to be delivered to the said mixer, or, when the gate to the mixer is closed, to deliver the material through said second delivery spout, and means for finally delivering the mixed material to a receptacle 30 or conveyer.
5. In a mixing apparatus, the combination of a supply hopper, a crushing feeder adjacent the discharge mouth of said hopper, an elevator, a separator to which material 35 from said feeder is delivered by said elevator, a mixer hopper to which the fine material is delivered from said separator, a pulverizer to which the tailings from said separator are delivered, a mixer, a gate between 40 said hopper and mixer, and which gate may be opened when desired, so that all of the ingredients of a batch delivered to the apparatus may be mixed at the same time, and means for discharging the completed mixture 45 from the mixing apparatus.
6. In a mixing apparatus, the combination of an elevator, a separator to which material is delivered by said elevator, and a 50 mixer to which the tailings from said separator are delivered, these parts being all closed, so as to be dust-proof and having closed or dust-proof connections.
7. In a mixing apparatus, the combination of an elevator, means for feeding materials to said elevator, a separator to which material may be delivered by said elevator, a mixer, and means for delivering the material from said separator to said mixer, these parts being all closed so as to be dust-proof and having closed or dust-proof connections. 55
8. In a mixing apparatus, the combination of an elevator, a separator to which material is delivered by said elevator, a pulverizer for reducing the tailings from said separator, and a mixer to which the materials from said separator and pulverizer are eventually all delivered, these parts being all closed so as to be dust-proof and having closed or dust-proof connections. 60
9. In a mixing apparatus, the combination of an elevator, means for feeding material to said elevator, a separator to which material is delivered by said elevator, a pulverizer for reducing the tailings from said separator, and a mixer to which the materials from said separator and pulverizer are eventually all delivered, these parts being all closed so as to be dust-proof and having closed or dust-proof connections. 65
10. In a mixing apparatus, the combination of a supply hopper, a breaking feeder adjacent the discharge mouth of said hopper, an elevator, a separator to which material is delivered by said elevator, a mixer to which the materials are delivered from said separator, a pulverizer for reducing the tailings from said separator, and an adjustable chute or spout arranged to divert discharged material in one or more directions. 70
11. In a mixing apparatus, the combination with an elevator, a separator to which material is delivered by said elevator, a mixer hopper into which the fine materials from said separator are delivered, a mixer to which the ingredients to be mixed are delivered from said mixer hopper, a discharge spout leading from said mixer hopper to a point outside of said mixer, a gate for opening or closing the entrance to said spout, and a gate between said hopper and said mixer; whereby the materials may be made to pass from said mixer hopper through the said mixer, or pass by said mixer to the final discharge spout, as may be desired. 75
- In testimony whereof I affix my signature, 120 in presence of two witnesses.
